(57) **CLAIM**

The ornamental design for a pneumatic therapy system, as shown and described.

DESCRIPTION

FIG. 1 is a top front perspective view of a pneumatic therapy system;

FIG. 2 is a front view of the pneumatic therapy system;

FIG. 3 is a rear view of the pneumatic therapy system;

FIG. 4 is a right side view of the pneumatic therapy system;

FIG. 5 is a left side view of the pneumatic therapy system;

FIG. 6 is a top view of the pneumatic therapy system;

FIG. 7 is a bottom view of the pneumatic therapy system; and,

FIG. 8 is a bottom front perspective view of the pneumatic therapy system.

The long, broken lines shown in the figures illustrate portions of the pneumatic therapy system that form no part of the claimed design. The short, broken lines shown in the figures illustrate stitching of the pneumatic therapy system that forms no part of the claimed design. The dash-dot lines shown in the figures illustrate the bounds of the claim that form no part of the claimed design.

1 Claim, 5 Drawing Sheets
